COMBINED CAN AND BOTTLE OPENER

William E. Gundelfinger, House Springs, Mo.

Application August 30, 1952, Serial No. 21,249

Term of patent 7 years

(Cl. D44—29)

To all whom it may concern:

Be it known that I, William E. Gundelfinger, a citizen of the United States, residing in House Springs, Jefferson County, Missouri, have invented a new, original, and ornamental Design for a Combined Can and Bottle Opener, of which the following is a specification, reference being had to the accompanying drawing, forming a part thereof.

In the drawing:

Fig. 1 is a top plan view of a combined can and bottle opener embodying my new design;
Fig. 2 is a side view thereof;
Fig. 3 is a bottom plan view thereof;
Fig. 4 is a front end view thereof, and
Figs. 5 and 6 are sectional views, taken at lines 5—5 and 6—6 of Fig. 1.

I claim:

The ornamental design for a combined can and bottle opener, substantially as shown.

WILLIAM E. GUNDELFINGER.
